UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,387,250.

Specification of Letters Patent. Patented Aug. 9, 1921.

Application filed September 23, 1919. Serial No. 325,609.

To all whom it may concern:

Be it known that I, CLARENCE B. FOWLER, a citizen of the United States, residing at New York, in the county of New York, State 5 of New York, have invented certain new and useful Improvements in Telephone-Exchange Systems, of which the following is a full, clear, concise, and exact description.

This invention relates to telephone 10 exchange systems and more particularly to a line circuit for use in such systems.

In some telephone exchange systems it is desirable that the subscriber may be enabled to control the line signaling device, as well 15 as the supervisory signaling device, of a link circuit connected with the line. This feature is especially desirable in case the subscriber desires to recall the operator.

It is the object of this invention to provide 20 an improved system of signaling between the subscriber and the operator, whereby it is possible for the subscriber to control the line signal independently of the connection of a link circuit with the associated line.

To attain this object in accordance with 25 a feature of the invention, means is provided associated with a line circuit whereby the connection of a link circuit with the line 30 renders the link circuit supervisory signaling device responsive to a subsequent deenergization of the line relay, and the line signaling device responsive to a subsequent energization of such relay without altering the 35 condition of the interconnected talking conductors.

This and other features of the invention not specifically mentioned above, will be apparent from the following specification and 40 the annexed drawing, which shows diagrammatically a telephone line circuit embodying the invention and a portion of an operator's cord circuit for coöperation therewith.

In the drawing, a line A connects a 45 subscriber's station of any usual type with a central office and terminates thereat in the usual jack 1. A line lamp 3 associated with the jack 1 is controlled by a line relay 4. A cord circuit B, of any usual type, provided 50 with a supervisory signaling lamp 5 and an operator's listening key 6 terminates in a plug 2 for connection with the line A, only sufficient portions of such cord circuit being shown to properly illustrate the invention.

55 A double wound sleeve relay 7 and a slow

release relay 8 coöperate with the line relay 4 to control the supervisory signaling lamp 5 and the line lamp 3 during a connection of the link circuit B with the line circuit A.

It is thought that the invention may be 60 more fully comprehended from the following description of the operation of the system shown on the drawing.

The subscriber at the station associated with the line A initiates a call in the usual 65 manner by removing the telephone receiver thereat, thereby operating relay 4 over a circuit established from battery through the right-hand winding of relay 4, one line conductor, the apparatus at the subscriber's station, the other line conductor and the left-hand winding of relay 4 to ground. Lamp 3 is lighted over a circuit established from battery through lamp 3, the normal contact 70 of relay 7 and the alternate contact of relay 4 to ground. In response to the lighting of lamp 3, the operator inserts plug 2 of link circuit B into jack 1 of line circuit A, thereby operating relay 7 over a circuit established from battery through supervisory 75 lamp 5, sleeve contacts of plug 2 and jack 1, and both windings of relay 7 to ground. The high resistance of such circuit prevents the lighting of lamp 5. The opening of the normal contact of relay 7 extinguishes line 80 lamp 3.

The number of the line desired may then be obtained by the operator by the actuation of the listening key 6, and the connection may be established with the called line 90 in the usual manner.

Upon completion of the conversation, the restoration of the receiver at the subscriber's station associated with the line A releases relay 4, thereupon operating slow-release 95 relay 8 over a circuit extending from battery through the winding of relay 8, the normal contact of relay 4 and the alternate contact of relay 7 to ground. Relay 8 thereupon locks in an operated condition over a circuit established from battery through the winding and the middle alternate contact of relay 8 and the alternate contact of relay 7 to ground. The closure of the right-hand contact of relay 8 short-circuits the high 100 resistance left-hand winding of relay 7, thereby sufficiently reducing the resistance in the circuit containing supervisory lamp 5 to permit the lighting of such lamp to 105 serve as a disconnect signal. Due to the 110

locking of relay 8 under the control of relay 7, the lamp 5 remains lighted while the plug 2 remains in the jack 1, but the removal of the plug, in response to the disconnect signal, 5 restores all apparatus to the normal condition.

However, in case the subscriber desires to initiate a recall, the removal of the receiver from the switchhook, while the plug 2 remains in the jack 1, causes the reoperation of relay 4 lighting the line lamp 3 over a circuit extending from battery through lamp 3, the left-hand contact of relay 8 and the alternate contact of relay 4 to ground. The 10 operator upon observing such recall signal, may actuate the listening key 6 and upon ascertaining that the subscriber desires another connection removes the plug 2 from the jack 1, thereby restoring the apparatus 15 to normal, and after reinserting the plug 2 into the jack 1, proceeds with the new call.

The condensers 9 and 10 are inserted in the line conductors to provide a path for the talking currents, which effectively prevents the passage of the direct current associated with the link circuit to the relay 4.

It will be noted that by means of this invention the subscriber may recall the operator during the continuance of a connection 30 by the relighting of the line lamp supplementing the lighting of the supervisory lamp of the cord circuit.

What is claimed is:

1. In a telephone exchange system, a line 35 circuit, a link circuit for connection therewith, a signaling device associated with the line circuit, a signaling device associated with the link circuit, a relay associated with the line circuit, a second relay controlled by the first relay, a locking winding for said 40 second relay, means for causing the second relay to lock in the operated position through its locking winding to maintain the link circuit signaling device in an operated condition during the continuance of the connection, and means for controlling by the joint action of both relays both signal 45 devices.

2. In a telephone exchange system, a line 50 circuit, a link circuit for connection therewith to establish a talking circuit including conductors of the interconnected line and link circuits, a relay associated with the line circuit, a signaling device responsive to the energization of the relay, a signaling device for the link circuit, means responsive to the connection of the link circuit with the line circuit to restore the first mentioned signaling device, means responsive to the 55 energization of the relay to operate the link circuit signaling device, and means independent of the talking circuit and responsive to a subsequent energization of the relay during the continuance of the connection to reoperate the line signaling device.

3. In a telephone exchange system, a line circuit, a link circuit for connection therewith, a relay associated with the line circuit, a signaling device responsive to the energization of the relay, a signaling device for the link circuit, means responsive to the connection of the link circuit with the line circuit to restore the signaling device associated with the line circuit, means responsive to the deenergization of the relay to operate the signaling device associated with the link circuit, means responsive to a subsequent energization of the relay during the continuance of the connection to reoperate the line signaling device and means for maintaining said supervisory signaling device in an operated condition during the continuance of the connection. 70

4. In a telephone exchange system, a line circuit, a link circuit for connection therewith, a signaling device associated with the line circuit, a signaling device associated with the link circuit, subscriber and operator controlled means for operating both signaling devices during the connection of the link circuit with the line circuit, and means for maintaining said link circuit signaling device in an operated condition independently of the subscriber controlled means. 85

5. In a telephone exchange system, a line circuit, a link circuit for connection therewith, a relay associated with the line circuit, a supervisory signaling device for the link circuit, a high resistance circuit completed therefor upon the connection of the link circuit with the line circuit, means responsive to a deenergization of the relay to reduce the resistance of the high resistance circuit thereby causing the operation of the supervisory signaling device, and means for maintaining the supervisory signaling device in an operated condition independently of subsequent energizations of the relay. 100

6. In a telephone exchange system, a line circuit, a link circuit for connection therewith, a relay for the line circuit, a signaling device controlled thereby, a supervisory signaling device for the link circuit, a second relay operating in response to the connection of the link circuit with the line circuit to restore the line signaling device, and a third relay operating upon the deenergization of the first mentioned relay and locking under control of the second relay to operate the supervisory signaling device, and a circuit for the line signaling device prepared by said third relay and completed upon a subsequent energization of the first mentioned relay to reoperate the line signaling device. 115

7. In a telephone exchange system, a line circuit, a relay associated therewith, a signaling device responsive to the energization of the relay, a link circuit for connection 120

with the line circuit, means responsive to the connection of the link circuit with the line circuit to remove the line signaling device from the control of the relay, and means 5 responsive to the deenergization of the relay to return the line signaling device to the control of the relay.

8. In a telephone exchange system, a subscriber's line circuit, a signaling device 10 therefor, a link circuit for connection with the line circuit, a signaling device therefor,

subscriber controlled means for operating both devices during a connection of the link circuit with the line circuit and operator controlled means for maintaining the link 15 circuit signaling device in an operated condition during the continuance of such connection.

In witness whereof, I hereunto subscribe my name this 19th day of September, A. D. 20 1919.

CLARENCE B. FOWLER.
